UNITED STATES PATENT OFFICE

2,273,337

METHOD OF LOADING MANIFOLDING DEVICES AND STATIONERY MATERIAL THEREFOR

Milton C. Stern, Dayton, Ohio, assignor to The Egy Register Company, Dayton, Ohio, a corporation of Ohio

Application December 26, 1940, Serial No. 371,666

3 Claims. (Cl. 282—21)

My invention relates to manifold stationery, and more particularly to an improved method of loading manifolding machines, such as autographic registers, billing machines, typewriters and auxiliary attachments.

It is an object of this invention to devise a method for attaching the end portion of one set of manifold paper webs to the leading web portion of a new pack of manifold paper webs whereby the machine or attachment is kept continuously loaded.

Another object is to provide a quick way of reloading the manifolding device with a new set of manifold paper webs without having to open the machine and manipulate it while threading each of the webs of the new set of stationery forms into the machine.

These and other objects and advantages will appear from the following description taken in connection with the drawings, wherein

Figure 1 is a fragmentary cross sectional view of an autographic register illustrating the feeding of manifold paper sheet forms from a zig-zag folded pack arranged in a register device;

Figure 2 is a plan view of manifold paper web forms illustrating the manner of attaching one set of manifold paper web forms to a succeeding set in accordance with my invention;

Figure 3 is a similar plan view of the attached paper web forms as shown in Figure 2 taken on the underside of the web;

Figure 4 is a fragmentary view showing an enlarged section taken through the manifold papers and carbon sheets of an autographic register device similar to that shown in Figure 1;

Figure 5 is a similar enlarged cross sectional detail view taken substantially on the line 5—5 of Figure 3 and illustrating the carbon sheet arranged between the paper web form;

Figure 6 is a similar plan view of a paper web form, as in Figure 2, showing the use of sealing wax for securing the forward leading edge of the new set of paper web forms to the trailing end of the used set of forms;

Figure 7 is a similar view as Figure 6 illustrating a modified method of attaching the paper web forms;

Figure 8 is a plan view illustrating another method of attaching the paper web forms.

In the use of manifolding devices, such as autographic registers and the like, it is necessary to reload the machine at intervals when the stationery sheet forms conventionally used become exhausted. This requires opening of the register or manipulating device, threading the leading

edges of each of the next set of manifold paper webs in position to be advanced through the machine by the feed rolls, and adjustment of the machine to bring the stationery paper forms in accurate alignment so that the machine can be properly operated. My invention eliminates this time consuming task and provides a method whereby the manifolding machine can be kept continuously loaded with stationery paper web forms.

In loading autographic registers by my improved method, a continuous web is provided wherein no projecting surfaces are formed at the junction between the two sets of manifold paper webs which would interfere with the transverse movement of the paper webs over the interleaved carbon sheets causing distortion or tearing of the same. The carbon paper sheets are positioned transversely to the writing table and the manifold paper sheet forms are moved transversely thereover so as to interleave the paper web forms with carbon paper. This arrangement requires that the manifold paper sheet forms present no protruding surface or abutment which might catch onto the edge of the carbon sheet and tear or distort the same during the use of the device. My improved invention eliminates any difficulty of this nature and provides a rapid and improved method of reloading the manifolding device with stationery.

Referring to the drawings in detail, in Figure 1 an autographic register device is shown having a writing table 10 over which paper web forms, generally designated 12, are drawn from a zigzag folded pack 13. This pack is disposed in the base of the register and fed forward over the table by manipulating the feeding roll means 15 in the conventional manner. Carbon paper sheets 17 are arranged transversely across the table 10 in the window or opening 19 and the paper web forms 12 are fed forward and transversely of the carbon sheets 17 during the use of the register.

As illustrated in Figure 2, the manifold paper comprises a continuous web 20 having spaced printed forms 21 between which are perforated or otherwise weakened sections 23 which permit detaching of the individual forms from the continuous web after use. Spaced file apertures 25 are suitably formed in the manifold paper webs for convenience in filing the forms after use.

In order to attach a new set of forms to the trailing end of one set, I have discovered that this can be effected, as illustrated in Figures 2, 3, 6, 7 and 8 so as to present an unobstructed

surface whereby the paper web forms can pass transversely over the thin carbon paper sheets without becoming snagged thereto or otherwise interfering with the carbon paper. To this end, I cut or sever the leading form of the succeeding continuous manifold paper web 26, as shown at 27, so as to present a pointed leading edge. The leading edges of the succeeding manifold paper web are preferably cut in the form of a peak and the apex, as illustrated at 29, suitably secured to the trailing end paper web form 20. This is suitably accomplished by applying a triangular shaped sticker 30 over the apex or pointed portion 29. The sticker 30 is preferably made of very thin material such as onionskin or "Scotch" tape and positioned so that it presents a leading point 32 which can readily pass over the edges of the carbon sheets 17, as illustrated in Figure 4. If desired, the forward leading edge of the sticker may be feathered or chamfered, as shown at 34 in Figure 5.

In mounting the pointed leading paper web portion 26 onto the trailing end form of the advanced paper web, the new paper web is laterally aligned therewith and the perforated section 23 placed in registration prior to adhesively uniting the two paper web forms, as illustrated in Figures 2 and 3. Thereafter, no further adjustment of the manifold paper sheets is necessary.

As a modification, sealing wax, such as shown at 36, may be used for adhesively uniting the apex portion 29 of the paper web sheet form 26 to the trailing end form of the paper web 20, as shown in Figure 6.

A further modification is illustrated in Figure 7 wherein the leading paper web form is serrated so as to form two or more pointed leading edges, as illustrated at 38, and wherein the apex portions 39 are adhesively united to the trailing paper web form 20 as by means of triangular shaped adhesive tabs 40, similarly as in Figures 2 and 3.

In Figure 8 there is illustrated another modification wherein the pointed flap portion 42 of the leading paper web form 26 is provided with adhesive or glue along the periphery, as shown at 43, and the forms attached together by moistening the adhesive portion 43 and pressing the same against the paper web 26 after properly aligning the paper web forms.

It will be understood that other suitable means for attaching the paper webs together may be used so long as the webs are joined together in such a manner that free passage of the paper web forms over the edges of the carbon sheet is afforded under all operating conditions.

The use of clips, pins, paper stapling means and the like may be used in place of the adhesive tabs and sealing wax provided the forward leading edges of the succeeding paper web forms are 5 securely fastened to the trailing paper web form provided the protruding fastening means is beveled so as to present no abutment means which might engage with the carbon sheet papers during the passage of the same thereover. Preferably, however, adhesive tabs formed of very thin sheet material are used as the fastening means.

It will be further understood that this invention is not limited to the particular shape of the serrated manifold paper webs which are to be secured to the trailing end form to provide a continuous manifold paper sheet and that such modifications as may be necessary to adapt my invention to varying conditions and uses may be made without departing from the spirit and scope of my invention.

Having thus fully described my invention, what I claim as new and desire to secure by Letters Patent is:

1. In a method of providing continuous reloading of manifold devices with stationery sheet material, the steps of overlapping the trailing end form of one set with the leading end form of the succeeding set, serrating the leading edge of said succeeding paper sheet form, applying adhesive to the underside of said serrated leading edge, and adhesively uniting said serrated portion to the trailing end form of said other paper web set by means of a triangular-shaped sticker having a feathered leading edge.

2. In a method of providing continuous reloading of manifold devices with stationery sheet material, the steps of severing the leading edge of the succeeding set of paper web forms to present a pointed end portion, overlapping said end portion in registration with the trailing end form of the forward paper web sheet, and adhesively attaching the peak portion of said pointed end portion to the trailing end form by means of a triangular shaped sticker.

3. As an article of manufacture, manifold paper webs which are adapted to be attached together, one of said paper webs comprising a peak shaped end portion which is adapted to be attached to the trailing end form of said other manifold paper web, and means comprising a triangular shaped sticker for adhesively attaching said peak shaped portion to the other sheet form.

MILTON C. STERN.
